UNITED STATES PATENT OFFICE.

EDWARD A. MULL, OF WAUSEON, OHIO.

METAL-BENDING TOOL.

1,420,731.

Specification of Letters Patent. Patented June 27, 1922.

Application filed April 29, 1921. Serial No. 465,491.

To all whom it may concern:

Be it known that I, EDWARD A. MULL, a citizen of the United States, and a resident of Wauseon, in the county of Fulton and State of Ohio, have made an Invention Appertaining to Metal-Bending Tools; and I do hereby declare the following to be a full, clear, and exact description of the invention, such as will enable others skilled in the art to which it appertains to make and use the same, reference being had to the accompanying drawings, and to the characters of reference marked thereon, which form a part of this specification.

My invention has for its object to provide a tool for bending sheet metal so as to turn one edge of the metal so as to produce a flange extending from the body of the sheet metal in a curved line, and at the same time to so form the flange that it will hold the body of the sheet metal in a curved surface. The invention particularly has for its object to provide a tool whereby automobile doors may be readily formed and which will have a curved upper flange that will produce a finished appearance, and will at the same time produce a curved surface on the body portion of the door.

The invention may be contained in structures of different forms, and to illustrate a practical application or embodiment of the invention I have selected a structure containing the invention as an example of such structures, and shall describe it hereinafter. The structure selected is illustrated in the accompanying drawings.

Figure 1 of the drawings is a transverse sectional view of the tool. Fig. 2 is an end and broken view of the tool. Fig. 3 is a sectional view showing the tool in a different position from that shown in Fig. 1. Fig. 4 shows an end view of the tool, the tool, however, being shown open. Fig. 5 is a top view of the tool. Fig. 6 is an edge view of the sheet metal after it has been bent. Fig. 7 is a perspective view of the door formed by the tool, on a reduced scale.

1 of the tool is the main supporting block, which has a concave surface 2 to correspond with the convex surface 3 of the door or other device that is to be shaped by manipulation of the tool. The surface 2 is formed of two parts 4 and 5 that extend at a slight angle to each other so as to form the portions 6 and 7 of the door. A movable block 8 is located on a pair of rods 9 and is provided with the surface 10 that corresponds to the

concave surface 2 that is formed of the concave surfaces 4 and 5. The surface 10 is convex in form to fit the portions 4 and 5 of the surface 2. At the vertex of the angle between the surfaces there is located a pair of rods 11 and 12 that extend the length of the parts 1 and 8. The parts 1 and 8 may be formed of wood if desired, and the rods 11 and 12 may be formed of metal which will give greater rigidity at the corner where the metal is to be bent.

The sheet metal 13 is inserted between the parts 1 and 8 of the tool, as shown in Fig. 4, and then the block 8 is forced towards the block 1 by means of the cams 14 to cause the sheet metal 13 to be bent in the shape shown in Fig. 6, except the flange portion 15, which is subsequently formed. The cams 14 are pivotally and eccentrically connected to the bar 16 located on the rods 9 by means of the pins 17. After the sheet metal 13 has been inserted in position the handles of the cams 14 are turned so as to cause the cams to force the block 8 towards the part 1 of the tool, and thus the first bend is made in the sheet metal.

The block 8 is also provided with a bar 18 which forms a clamping edge and has the curvature of the portion 5 of the surface 2. It may also have the slight upward curvature to form the curvature of the flanges 15, as shown in Fig. 6. A block 19 is pivotally connected to the block or supporting part 1 of the tool by pivots located substantially in line with the upper edge of the bar 18. A pair of arms 20 are connected to the block 19, and a pair of arms 21 are secured to the block 1 and are pivotally connected together by pivot pins located in their ends 22. The center lines of the pivot pins are substantially in line with the upper edge of the bar 18.

A pair of bars 23 and 24 are provided that may be clamped on opposite sides of the portion of the sheet material that is to form the flange 15. The bars 23 and 24 are rigid, but are sufficiently flexible to bend under the considerable pressure to which they are subjected in the manipulation of the tool. They thus provide a means for securely clamping the flange portion of the sheet material, and yet will flex under the pressure to which they are subjected. The bar 24 is located against the face of the block 19 and between the flange portion of the sheet material and the block 19. The bar 23 is then placed on the bar 18 and is clamped by means of the

clamps 25 that has a screw 26 that extends through openings formed in the block 19 and so as to press against the bar 24. In order to hold the clamps 25 in place the block 19 may be recessed, and portions of the brace or body of the clamp may be inserted in the recess thus formed. The block 19 is then moved angularly about the pivot pin located in the ends 22 of the arms 20 and 21, and the clamps and the bars 23 and 24 are carried over with the block 19.

In order to produce the curvature of the flange 15, the block 19 is provided with a plurality of cams 27 that are pivotally and eccentrically connected to the block 19 and are located in recesses formed in the block. They are provided with handles 28 that extend through brackets 29 that are secured to the supporting part 1 of the tool. The handles 28, however, slide in the brackets 29 when the block 19 is turned over, since the pivot pins of the cams 27 are not in alignment with the pivot pins located in the ends 22 of the arms 20 and 21. The cams 27, when the block 19 is in the position shown in Fig. 1, have their surfaces located in definite relation relative to the surface of the block, and so as to make contact with the surface of the bar 24. The position of the surfaces of the cams 27 may be varied according to the curvature that it is desired to form in the flange 15, and according to the relative position of each of the cams with reference to the center line of the sheet material extending through the body of the sheet material and the flange. When, therefore, the block 19 is turned over the cams 27 follow the movement of the bars 23 and 24 and bend in response to the pressure of the surfaces of the cams 27 since the bars are pushed under the cams 27, as shown in Fig. 3. This operates to draw the metal along the center line extending through the center of the body of the sheet material and the flange, while the ends of the bars may be dipped down to cause the flange to conform to the curvature desired to be produced in the flange.

The bars 18 and 23 may be provided with bevelled edges, particularly at their ends, in order that they may be turned sharply relative to each other.

The tool may be opened for performing sequential operations of the tool by opening the blocks 1 and 8, which is done by merely drawing the arms of the cams 14 outward, or to the opposite sides of the pivot pins 17. The blocks 1 and 8 are provided with recesses in which are located the compression springs 30 which will cause immediate separation of the blocks 1 and 8. The block 8 will slide along the rods 9. The clamps 25 may then be opened and the bars 23 and 24 removed and the shaped sheet material article removed. The operations may be re-

peated, thus quickly bending successive sheets of metal into the desired form.

I claim:

1. In a metal bending tool, a block having a surface conforming to the surface of the article that it is desired to form, a second block having a surface matching the surface of the first named block, means for clamping the blocks together to bend the sheet metal, a pair of clamping members, means for rotating the clamping members, and means for moving portions of the clamping members through greater lengths during their rotation than other portions of the clamping members. 80

2. In a metal bending tool, a member having a surface conforming to the shape of the surface of the article to be formed, a second member having a similar surface, means for clamping the members, a pivoted member having flexible clamping parts, and means for positively altering the shape of the flexible clamping parts as the pivoted member is moved about the axis of its pivot. 85

3. In a metal bending tool, a member having a surface conforming to the shape of the surface of the article to be formed, a second member having a similar surface, means for clamping the members, a pivoted member having flexible clamping parts, and means for positively altering the shape and position of the flexible clamping parts as the pivoted member is moved about the axis of its pivot. 90

4. In a metal bending tool, a member having a surface conforming to the shape of the surface of the article to be formed, a second member having a similar surface, means for clamping the members, a pivoted member having flexible clamping parts, 105 cams for positively bending the flexible clamping parts as the pivoted member is moved about the axis of its pivot. 100

5. In a metal bending tool, a member having a surface conforming to the shape of the surface of the article to be formed, a second member having a similar surface, means for clamping the members, a third member having a flexible clamping means, and means for altering the shape and position of the flexible clamping means and pivotally connected to the said third member. 110

6. In a metal bending tool, a member having a surface conforming to the shape of the surface of the article to be formed, a second member having a similar surface, means for clamping the members, a third member pivotally supported and having a flexible clamping means, cams coacting with the flexible clamping means for bending the sheet material as the said third member is rotated. 120

In testimony whereof, I have hereunto signed my name to this specification.

EDWARD A. MULL.
